UNITED STATES PATENT OFFICE.

FREDERICK HACHMANN AND WALDEMAR ERICKSEN, OF MINNEAPOLIS, MINNESOTA,
ASSIGNORS TO ACME MANUFACTURING COMPANY, OF ST. PAUL, MINNESOTA, A COR-
PORATION OF MINNESOTA.

CAR-AXLE-BOX LID.

No. 875,809.

Specification of Letters Patent.

Patented Jan. 7, 1908.

Application filed February 16, 1906. Serial No. 301,387.

To all whom it may concern:

Be it known that we, FREDERICK HACHMANN, a citizen of the United States, and WALDEMAR ERICKSEN, a citizen of the Kingdom of Denmark, both residing at Minneapolis, in the county of Hennepin and State of Minnesota, have invented certain new and useful Improvements in Car-Axle-Box Lids; and we do hereby declare the following to be a full, clear, and exact description of the invention, such as will enable others skilled in the art to which it appertains to make and use the same.

Our invention has for its object to provide an improved car axle box lid, and to this end it consists of the novel devices and combinations of devices hereinafter described and defined in the claims.

The improved device involves a supporting arm which is hinged or pivoted to the axle box, and a lid which is mounted on and carried by said supporting arm, and is connected thereto in such manner that when rotated or moved pivotally, it will move laterally with respect to the said arm to and from engagement with the lid seat and the said box.

As illustrated in the drawings and as hereinafter specifically described, provision is made whereby the said arm will be locked to the box in a position to hold the lid in a closed position, and the lid is arranged to interlock with the box when seated against the same, in such manner that the said supporting arm is in turn locked in the supporting position stated.

Two forms of the improved device are illustrated in the accompanying drawings, wherein like characters indicate like parts throughout the several views.

Referring to the drawings: Figure 1 is a view in front elevation, showing a car axle box having applied thereto an improved journal box lid designed in accordance with our invention. Fig. 2 is a side elevation of the parts shown in Fig. 1, a portion of the box being broken away. Fig. 3 is a view corresponding to Fig. 2, but showing the lid in an open position, some parts of the box and lid being broken away. Fig. 4 is a vertical section taken on the line $x^4 x^4$ of Fig. 1, some parts being broken away. Fig. 5 is a detail in plan view, showing the hinge bolt

which pivotally connects the lid-supporting arm to the axle box. Fig. 6 is a view corresponding to Fig. 1, but illustrating a modified construction. Fig. 7 is a section taken on the line $x^7 x^7$ of Fig. 6, some parts being broken away. Fig. 8 is a view in side elevation, some parts being broken away and some being sectioned, of the parts shown in Fig. 6. Fig. 9 is a detail view in plan, illustrating a modified construction of the lid hinge bolt, and Fig. 10 is a detail view in side elevation, showing a form of hinge lug used in connection with the bolt shown in Fig. 9.

Attention is first directed to the construction illustrated in Figs. 1 to 5, inclusive. The axle box 1 is of the usual construction, except that in its open outer face it is formed with an annular flange 2 that affords a seat for the axle box lid 3. This axle box lid 3 is of disk-like form, and, on its outer face, is formed with an annular groove that receives and closely fits the annular rim or seat of the box. The axle box 1 is provided with a heavy hinge lug 4, in which is rigidly secured the hinge bolt 5, the projecting ends of which are flattened at 6, thereby affording an angular trunnion-like projection at each side of said bolt. The hinge bolt 5 is rigidly secured in the lug 4, by means of a set screw 7, but it may be otherwise secured, and the angular trunnion may be otherwise formed. The lid 3 has a screw-threaded center hub portion that works on a threaded stud 8, formed at or rigidly secured to the free end of a lid-supporting arm 9. This lid-supporting arm 9 is bifurcated, and in the upper ends of its prongs seats 10 are formed, that adapt the lid-supporting arm 9 to move pivotally upon the angular trunnions 6. The seats 10 are formed with angular extensions 10^a and 10^b that extend at an angle of about 90 degrees to each other. The numeral 11 indicates a coiled spring that surrounds the threaded stud 8 to the arm 9, and is attached at one end to said arm 9, and at its other end to the lid 3. The tension of the spring 11 is such that it tends to rotate the lid 3 on the stud 8, in a direction to move the said lid away from the arm 9 and against its annular seat 2 on the box.

The relative arrangement of the parts described is such that when the lid-supporting arm 9 is turned pivotally downward and then

moved so as to carry the seat extensions 10^a onto the angular trunnions 6, said arm will be locked against rotation and will hold the lid 3 in position with engagement with its seat 2 on the box. The said arm when thus interlocked with the fixed angular trunnions 6 offers a base of action for the lid 3, and the lid then being allowed to turn under the tension of the spring 11, or being otherwise turned 10 in the direction of the arrow marked on Fig. 1, will be moved into engagement with the seat 2 on the box, and the annular groove on its inner face, when pressed onto the said seat 2, will interlock the lid to the box in 15 such manner that the arm 9 cannot be moved out of interlocking engagement with the fixed trunnions 6. The lid is then securely interlocked in its closed engagement with its seat on the box, and the box is tightly closed 20 in such manner that oil cannot escape from the box, and dust or dirt cannot enter into the box.

To move the lid into an open position, it is first necessary to rotate the same on the 25 threaded stud 8 and against the tension of the spring 11, in a proper direction to carry the lid toward the arm 9, and far enough away from the annular seat 2, to permit the lid to move upward clear of the said seat 2. 30 When this is done the arm 9, together with the lid, may be moved upward far enough to carry the seats 10 into line with the fixed angular trunnions 6, and this being done the arm 9 may be moved pivotally upward together with the lid, approximately into position shown in Fig. 3, and then by engaging the seat extensions 10^b with the fixed trunnions 6, the said arm 9 will be interlocked to the box, as shown in Fig. 3, and the lid will 40 be securely held in open position.

The spring 11 may of course be dispensed with, but is desirable because it serves to hold the lid in a closed position tightly against the box, and prevents the same from being 45 jarred or otherwise accidentally opened or unseated.

The construction illustrated in Figs. 6, 7 and 8 is like that already described, except as hereinafter noted. In this construction 50 the supporting arm 9', at its free end, instead of having a threaded stud as previously described, is formed with diametrically projecting cam blades 12, the peripheral ends or portions of which extend at an angle to the 55 face of the lid so that they act as segmental threads. These cam blades or segmental threads work in correspondingly formed cam seats 13 in segmental lug-like projections 14, that are cast integral with or otherwise rigidly secured to the outer face of the lid 3^a. The cam blades 12 and their cam seats 13 act 60 very much like the screw-threaded stud and hub of the previously described construction, but operate to move the lid into and out of engagement with the seat on its box more rapidly.

idly, or, in other words, under a much less rotary movement of the lid. Considerably less than 45 degrees of rotary movement of the lid, with respect to the supporting arm 9', will with this latter described connection 70 serve to move the lid from its seated position into a position to clear the box, or vice versa. To prevent accidental unseating of the lid under jar incident to the service, the seat lid is shown as provided with an over-poising 75 weight 15 in the form of a heavy lug cast on the inner face thereof. Also, in this construction the lid-supporting arm 9' is extended downward, and is terminated in a lock lug 9^a that engages with the co-operating lock lug 1^a on the box 1, to hold said lid in a closed position. This interlocking engagement of the lower end of the arm 9' and the box relieves the pivotal connection of the arm to the box from strains, and permits the 80 said arm and the said pivotal connection to be made much lighter than would otherwise be practicable; and, furthermore, makes it possible to eliminate the interlocking pivotal connection, although this latter is desirable 85 in order to hold the lid in an open position. In both of the constructions above described the lid is shown as provided with several marginal lugs 16, that are adapted to be struck with a hammer or taken hold of by 90 the hand, to impart an initial rotary movement to the lid necessary to unseat the same from the box.

In Fig. 9 we have shown a hinge bolt 5^a, having a flattened central portion 6^a. In 100 Fig. 10 the bolt seat 10' in the hinge lug 4^a of the box is provided with angular extensions 10^c and 10^d, for engagement with the flattened central portion 6^a of the bolt 5^a. With this construction the ends of the hinge 105 bolt 5^a should be rigidly secured to the prongs of the arm 9', and the flattened central portion 6^a thereof should be engaged with the seat extensions 10^c, to lock the arm 9' in position to hold the lid closed, and 110 would be engaged by the seat extension 10^d and hold the arm and lid in a raised position corresponding to the position shown in Fig. 3.

The lid above described and associated devices for supporting the same, are of comparatively small cost, are strong and durable and efficient for the purposes had in view. The lid may be very quickly and easily opened and closed, and when closed tightly closes the box. 115

We claim as our invention:

1. The combination with an axle box and a lid, of a lid supporting arm connected to said box by an interlocking pivotal joint, and the said lid being connected to said arm with freedom for lateral movements with 125 respect thereto to and from a seated position on the box, when said arm is interlocked to the said box, substantially as described.

2. The combination with an axle box having an annular lid seat, of a lid-supporting 130

arm connected to said box by an interlocking joint, and a lid having a threaded or spiral engagement with said arm, whereby said lid may be rotated and moved laterally toward 5 and from said arm to and from a seated position on said box, substantially as described.

3. The combination with an axle box, having an annular lid seat, of a lid supporting arm connected to said box by an interlocking 10 pivotal joint, and a lid having a threaded or spiral engagement with said arm, whereby the said lid may be moved laterally toward and from said arm, and to and from a seated position on the box, substantially as described.

4. The combination with an axle box, of a lid-supporting arm connected to said box by an interlocking pivot, arranged to lock 20 said arm in either of two positions, and a lid having a threaded or spiral engagement with said arm, whereby it may be rotated and will be moved laterally with respect to said box, substantially as described.

5. The combination with an axle box, of 25 a lid-supporting arm connected thereto by a pivot joint arranged to lock said arm in a position to hold said lid in a seated position, and a lid having threaded or spiral engagement with said arm adapting it to rotate and 30 to move laterally with respect to said arm, to and from a seated position with respect to said box, and which lid, when seated against said box, interlocks therewith and holds said arm interlocked with said box, 35 substantially as described.

6. The combination with an axle box, of a lid-supporting arm connected thereto for 40 pivotal and endwise sliding movements and

having at its free end interlocking engagement with the box, under its endwise movements, and a lid connected to said arm and movable with respect thereto into and out of engagement with the box, substantially 45 as described.

7. The combination with an axle box, of 45 a lid-supporting arm connected thereto for pivotal and endwise sliding movements, and having interlocking engagement with the box at its free end, under its sliding movement, and a lid connected to the intermediate portion 50 of said arm by threaded or spiral engagement by means of which it may be moved laterally with respect to said arm into and out of engagement with the box, substantially as described.

8. The combination with an axle box, of 55 a lid supporting arm connected thereto for pivotal and sliding movements, and having interlocking engagement with the box, under its sliding movements, and a lid connected 60 to said arm, by a device permitting said lid to move laterally with respect to said arm to and from a seated position on the box, said lid having interlocking engagement with the box, when seated thereon, and arranged 65 to lock said arm against sliding movement and hence interlocked to the box, substantially as described.

In testimony whereof we affix our signatures in the presence of two witnesses.
